Patented Nov. 30, 1976

242,571

PLANTER-ASHTRAY

Troy Dunn, 3445 Oceanview Blvd.,
San Diego, Calif. 92113

Filed Aug. 25, 1975, Ser. No. 607,551

Term of patent 14 years

Int. Cl. D11—02; D27—03

U.S. Cl. D6—182

Fig. 1

Fig. 2

Fig. 3

Fig. 4

FIG. 1 is a perspective view of a planter-ashtray, showing my new design;

FIG. 2 is a top plan view thereof;

FIG. 3 is a bottom plan view thereof; and

FIG. 4 is a side elevational view as taken from the rear of FIG. 1, with a plant indicated in broken lines for illustrative purposes only.

I claim:

The ornamental design for a planter-ashtray, as shown and described.
